(57) **CLAIM**

I claim the ornamental design for a headwear with camera, as shown and described.

DESCRIPTION

FIG. 1 is a top perspective view of a headwear with camera according to the new design.

FIG. 2 is a front elevational view of the headwear with camera depicted in FIG. 1.

FIG. 3 is a rear elevational view of the headwear with camera depicted in FIG. 1.

FIG. 4 is a right side elevational view of the headwear with camera depicted in FIG. 1.

FIG. 5 is a left side elevational view of the headwear with camera depicted in FIG. 1.

FIG. 6 is a top plan view of the headwear with camera depicted in FIG. 1; and,

FIG. 7 is a bottom plan view of the headwear with camera depicted in FIG. 1.

The broken lines and unshaded areas adjacent to the broken lines depict portions of the headwear with camera that form no part of the claimed design.

1 Claim, 5 Drawing Sheets
